UNITED STATES PATENT OFFICE.

MATTHEW T. CHAPMAN, OF AURORA, ILLINOIS, ASSIGNEE TO THE AMERICAN WELL WORKS, OF AURORA, ILLINOIS, A CORPORATION OF ILLINOIS.

WELL-SINKING APPARATUS.

1,079,539.

Specification of Letters Patent.

Patented Nov. 25, 1913.

Application filed March 13, 1909. Serial No. 483,264.

To all whom it may concern:

Be it known that I, MATTHEW T. CHAPMAN, a citizen of the United States, residing at Aurora, in the county of Kane and State of Illinois, have invented certain new and useful Improvements in Well-Sinking Apparatus, of which the following is a specification, reference being had to the accompanying drawings.

10 My invention relates to well-sinking apparatus, and has for its object to provide certain improvements in apparatus for boring or drilling deep wells, such improvements relating to the mechanism for gripping the well-tube or boring-pipe so that it may be rotated and at the same time be free to descend as the depth of the well increases, and also so that it may be "jumped" when desired; to mechanism for supporting the 15 well-tube and holding it against rotation while sections of the well-tube are added or removed and for holding the pipe from falling back into the well when being drawn out should the hoisting tackle give out; and to 20 certain other features of construction which are hereinafter particularly pointed out.

In a general way it may be stated that well-sinking apparatus of the type to which my present application relates is shown in 25 Patent No. 382,689, granted to me May 15, 1888, in Patent No. 409,272, granted to me August 26, 1899, and in Patent No. 775,417, granted to me November 22, 1904; also in my pending application, Ser. No. 329,237, filed August 4, 1906.

In the accompanying drawings,—Figure 1 is a plan view of my improved apparatus, showing the devices for gripping the well-tube and rotating it for well-sinking purposes; Fig. 2 is a vertical section on line 2—2 of Fig. 1; Fig. 3 is a side elevation illustrating my said apparatus when arranged for adding or removing a section of pipe; Fig. 4 is a view showing the parts 40 shown in Fig. 3, the turntable being in vertical section, on line 4—4 of Fig. 5; Fig. 5 is a plan view of the arrangement shown in Fig. 3; Fig. 6 is a horizontal section on line 6—6 of Fig. 4; Fig. 7 is a cross-section on 45 line 7—7 of Fig. 1; Fig. 8 is a partial vertical section on line 8—8 of Fig. 9; Fig. 9 is a horizontal section on line 9—9 of Fig. 8; Fig. 10 is a vertical sectional view showing the tubular center of the turntable and the 50 disk-holding frame; Fig. 11 is a plan view

of the tubular center of the stationary base of the turntable; Fig. 12 is a bottom view of the rotary disk-holding frame; Fig. 13 is an edge view of the lever for turning the clamping wheels; and Fig. 14 is a view 60 showing said lever in operative position.

A well-sinking apparatus of the type to which my present application relates comprises, generally speaking, a turntable composed of a stationary member or base and 65 a rotary member which is caused to rotate about a vertical axis on said base. The rotary member carries suitable gripping mechanism adapted to engage and grip a round pipe for rotating it, meanwhile permitting endwise movement thereof through the gripping devices which consists usually of rotary disks mounted in a suitable frame and having sharp corners which engage the pipe or well-tube and bite into it sufficiently 70 to compel its rotation with the rotary member of the turntable. The gripping devices are mounted in a suitable frame or frames which are vertically movable upon guide-rods or standards in such manner as to permit the grippers to move up and down with the well-tube when the latter is 75 "jumped." In the operation of boring a suitable bit is placed at the lower end of a section of well-tube, and when the well has 80 been bored to such a depth as to receive the greater part of the well-tube, a second section is added by screwing it into a coupling at the upper end of the first section. Additional sections are added from time to 85 time as required, so that the well-tube may consist of a large number of sections. In removing the well-tube from the well the operation is reversed, the well-tube being 90 lifted to expose a coupling, when it is supported and held against rotation, while the uppermost section is removed by unscrewing it from the coupling—this operation being repeated until the several sections are 95 successively removed. With this explanation of the general construction and operation of well-sinking apparatus of the type illustrated in the drawings, I will now proceed to describe the apparatus illustrated 100 with special reference to the novel features 105 therein shown.

Referring to the drawings,—15 indicates the base or stationary portion of the turntable, which is supported on beams 16—17, or in any other suitable way. The base 15 110

is generally circular in form and is provided with an upwardly-projecting central sleeve 18 considerably greater in diameter than the well-tube. At its upper end the 5 sleeve 18 is provided with a series of internal notches or recesses 19, best shown in Figs. 10 and 11, placed equally distant apart to receive radial lugs 20 carried at the lower margin of a frame 21 designed to support a 10 series of disks 22, or equivalent devices, by which the well-tube is engaged and held against rotation while sections are being added to or removed from it. The frame 21 fits closely upon the upper end of the 15 sleeve 18 and is provided with a radial flange 23 which rests upon the upper edge of said sleeve 18, said frame when in position being as illustrated in Fig. 2. The frame 21 also serves as a cover-plate to substantially close the upper end of the sleeve 18 about the well-tube.

The disks 22 are best shown in Figs. 8 and 9, from which it will be seen that they are provided with a series of grooves making a series of parallel ridges which are sharp and are adapted to engage and bite into the well-tube 24. The several disks are mounted eccentrically upon pivots 25 suitably secured in the frame 21, the pivots 30 being below the centers of the disks so that the disks may be caused to swing toward the well-tube in the manner shown in Fig. 8. A hinged collar 26 is secured around the well-tube below one of the coupling sleeves 27, as shown in Figs. 4 and 8, and rests upon the disks 22 so that the weight of the well-tube transmitted through the collar 26 is applied to the upper surfaces of the disks and presses them firmly 40 into contact with the well-tube, thereby causing them to engage it firmly and prevent its rotation.

In Fig. 4, and also in the other figures, I have shown another form of gripping device used in lieu of the disks 22, the same comprising segmental blocks or pawls 28 which are mounted upon the pivots 25 and are adapted to swing into engagement with the well-tube 24 so as to engage the same 50 in the same manner as do the disks 22. The engaging faces of the blocks 28 are serrated, as shown in Fig. 6, so that they bite into the well-tube and prevent its rotation. The projecting portions of the blocks 28 which 55 engage the well-tube are made angular, as shown at 29 in Fig. 4, and the collar 26 rests upon them, thereby forcing them into biting engagement with the well-tube in the manner already described. Thus the 60 well-tube is not only supported against descent and prevented from falling back into the well when being drawn out should the hoisting tackle give way, but is held against rotation so that the section of the well-tube 65 above the coupling 27 may readily be re-

moved by unscrewing it. By making the central sleeve of the stationary portion of the turntable an integral part of the base, as shown, the structure as a whole is made much stronger and more secure and also 70 the gripper supporting frame 21 is convenient of access and may be more readily put in place or removed.

The construction of the collar 26 is fully illustrated and described in my pending application above referred to and therefore need not be described in detail here. It will suffice to say that it is composed of two semicircular members connected at one side by a hinge 30 and at the other side by a link 31 which swings in a recess 32 in lips 33 which project at the sides of the collar members opposite the hinge 30. The link 31 is adapted to swing over upon the members of the collar, as shown in Fig. 4, so as to lie 85 flush with the upper surface thereof, and is long enough to project under the coupling sleeve 27, as shown therein. Thus the weight of the well-tube rests upon the upper end of the link 31 when the latter is in operative 90 position and effectually prevents its displacement.

The parts of the mechanism thus far described are all stationary. That is to say, they do not rotate, as they are all supported by the stationary portion of the turntable. The rotating portions of the apparatus are carried by the upper or rotary member of the turntable 34, which overlies the base of the turntable and encircles the central sleeve 18, as shown in Figs. 1, 2 and 4. The rotary member 34 is mounted on anti-friction rollers 35 fitted in suitable runways in the members of the turntable and is driven by a gear 36 which meshes with an annular rack 37 on the under side of the rotary member of the turntable, as shown in Fig. 2, said gear being mounted on a shaft 38 driven from any suitable source of power. The upper member of the turntable is centered and held down in proper position by guide-rollers 39-40 which are mounted on the base of the turntable in suitable supports 41-42, respectively, as shown in Fig. 3. The supports 41 for the rollers 39, in the construction shown, are composed of inverted U-shaped frames having a slot which is radial relatively to the turntable, said slot receiving the pivot of the roller, as shown in Fig. 3, so that the roller may be adjusted toward and from the turntable. The supports 42 which carry the rollers 40 are in the form of L-shaped brackets mounted on the stationary member of the turntable, the rollers 40 being carried by pivots fitted in suitable bearings in the vertical portions of said standards. The rollers 39 are mounted to rotate on vertical axes and run in a groove 43 in the periphery of the turntable member 34, while the rollers 40 rotate on horizontal 130

axes and bear on an annular flange 44 which forms the lower margin of said groove 43. 45—46 indicate uprights or standards which rise from the rotary member of the turntable at diametrically opposite points and are secured at their lower ends in sockets 47—48, respectively, preferably by set-screws 49. The standards 45—46 serve not only to support and guide the gripping devices by which the well-tube is rotated in boring, but also to support the wrenches employed in screwing and unscrewing the pipe sections, as will be hereinafter described. 51—52 indicate sockets provided on the rotary member of the turntable at opposite sides of the socket 47, and 53—54 indicate similar sockets placed at opposite sides of the socket 48. The sockets 47, 51 and 52 are connected by webs 55, and in like manner 20 the sockets 48, 53 and 54 are connected by webs 56 for strengthening purposes. The sockets 51 and 52 are to receive upright rods or standards 57—58, and the sockets 53 and 54 are to receive upright rods or standards 25 59—60, respectively, as shown in Figs. 5 and 6. Said standards 57, 58, 59 and 60 are employed only when the pipe sections are being screwed or unscrewed,—at other times being removed so that the central standards 30 45—46 only are used when boring. The devices for gripping the well-tube in boring are best shown in Figs. 1, 2 and 7. As best shown in Figs. 1 and 7, each upright 45—46 carries a double-ended screw-shaft 61 provided with a hub 62 which slides upon the standard 45 or 46 and carries at its ends oppositely-disposed hand-wheels 63—64 which screw upon its ends. The hand-wheels 63—64 are provided with globular 35 hubs 65 which bear in suitable sockets in cross-heads 66—67, shown in Figs. 2 and 7. The cross-heads 66—67 each support two parallel horizontal shafts which carry gripping rollers which engage the well-tube, as 40 hereinbefore described,—68—69 indicating the shafts carried by the cross-head 66 and 70—71 those carried by the cross-head 67. 72—73 indicate the rollers carried by the shafts 68—69, and 74—75 those carried by 45 the shafts 70—71. As best shown in Figs. 1 and 7, the rollers of each pair are at opposite sides of the center of the well-tube 24, and the four rollers in the same horizontal plane accordingly engage the well-tube at 50 points practically ninety degrees apart. From the foregoing description it will be seen that the cross-heads 66—67 are in effect equalizers that are free to rock upon the tubular hubs 65 of the hand-wheels 63—64, and consequently the rollers upon the upper and lower shafts may accommodate themselves more perfectly to the well-tube, thus 55 securing a better gripping effect. Besides, they also adapt themselves better to the movement of the pipe when the latter is 60 “jumped” and avoid the clamping and binding at such times as is the case in prior constructions. Furthermore, this construction better accommodates itself to the passage of the pipe couplings, as the rocking frame which carries the gripping devices may swing out at the top and in at the bottom, or out at the bottom and in at the top, as may be necessary to permit a coupling to pass. The several hand-wheels may be 65 independently adjusted so that the proper contact of the several grippers may readily be obtained. In order to turn the hand-wheels 63—64 more tightly and thus secure a better engagement between the several 70 rollers of the well-tube, I provide a lever 76 having a pin 77 in one end adapted to enter holes 78 in the hand-wheels near the periphery thereof and also having a segmental guide-portion 79 which bears against 75 the periphery of the hand-wheel which is preferably tubular in form, as shown at 80 in Fig. 14. The ends of the guide 79 extend laterally at both sides of the median line of the lever, and consequently when the 85 lever is applied to the hand-wheel and pulled in either direction it acts to rotate the hand-wheel accordingly. 81 indicates legs which depend from the cross-heads 66—67 and when the cross-heads are in their 90 lowermost position rest upon ways 87 which extend transversely of the upper member of the turntable. 95 When a section of pipe is to be applied or removed the well-tube is supported in the 100 manner already described, by the collar 26, and the standards or posts 57, 58, 59, and 60 are applied to their respective sockets, the three posts at each side being connected to each other at the top by connecting bars 105 82—83, as shown in Figs. 4 and 5. Pipe wrenches are then applied to the intermediate standards 45—46, as shown in Fig. 4, said wrenches being preferably of the type 110 shown and consisting of a lever 84 and chain 85, the chain being adapted to encircle the pipe and be engaged by a serrated jaw 86 at the inner end of the lever. The outer end of the wrench is fitted in a suitable clamp or socket 88 vertically adjustable upon the 115 standard 45 or 46 so that it is held firmly in position, the connection between the wrench and the standard being virtually a pivotal connection. It will be apparent that the lower section of the well-tube being held 120 against rotation by the clamping devices hereinbefore described, when the upper member of the turntable is rotated in a direction opposite to that in which it is rotated for well-sinking purposes, the upper 125 section of the well-tube may be unscrewed and removed. In like manner, by properly applying the wrenches in inverted position and rotating the upper section of the turntable in the same direction as in sinking the 130

well the upper section of pipe may be 5 screwed into the coupling and thereby united with the lower portion of the well-tube. It will be understood that the levers 84 may be slid back through the loops of the clamps 88 when not in use, being held thus in readiness for application to the pipe at the proper elevation without the necessity for their being lifted, being thus slid back 10 if desired after each screwing or unscrewing operation during the proper manipulation of the pipe sections for the next succeeding operation. Moreover, by this arrangement, the wrenches are very readily adjusted for 15 pipes of different sizes. When drilling the gripper-supporting frame 21 is, of course, removed, but it is readily put in position when required.

Instead of using the style of pipe-wrench 20 shown, any other suitable devices for the purpose may be employed.

That which I claim as my invention, and 25 desire to secure by Letters Patent, is,—

1. In a rotary well-sinking machine, the 26 combination of a stationary turntable member comprising a base having a central opening for the passage of the boring tools and an integral upwardly-extending support 30 around said opening, a rotary member fitting around said support, anti-friction rollers supporting said rotary member, and means detachably connected with said support for holding the well-tube or boring device from 35 rotation when another section of tubing is connected thereto by rotation.

2. In a rotary well-sinking machine, the 40 combination of a stationary turntable member comprising a base having a central opening for the passage of the boring tools and an upwardly-projecting sleeve around said 45 opening, a rotary member fitting around said sleeve, anti-friction rollers supporting said rotary member, and means detachably connected with said sleeve for holding the well-tube or boring device from rotation when another section of tubing is connected thereto by rotation.

3. A well-sinking apparatus having a non- 50 rotary base having a central opening for the passage of the well-tube and a removable support having pivoted gripping devices adapted to be thrown forward into engagement with the well-tube for supporting it against downward movement and to be thrown back out of engagement therewith to 55 permit the passage of the well-tube downward.

4. In a well-sinking apparatus, the combination of a turntable comprising a lower 60 stationary member and an upper rotary member, said stationary member having a central opening for the passage of the well-tube, a support adapted to non-rotatably engage 65 said stationary member, and means carried

engagement with the well-tube for supporting the same against downward movement.

5. In a well-sinking apparatus, the combination of a turntable comprising a lower stationary member and an upper rotary member, said stationary member having a central opening for the passage of the well-tube, a support adapted to non-rotatably engage 70 said stationary member, and gripping devices carried by said support and movable into and out of engagement with the well-tube for supporting the same against downward movement and holding the same against rotation.

6. In a well-sinking apparatus, the combination of a turntable comprising a lower stationary member and an upper rotary member, said stationary member having a central opening for the passage of the well-tube, a separable support adapted to non-rotatably engage 75 said stationary member, and means carried by said support and actuated by the weight of the well-tube for gripping the same.

7. In a well-sinking apparatus, the combination of a turntable comprising a lower stationary member and an upper rotary member, said stationary member having a central opening for the passage of the well-tube, a separable support adapted to non-rotatably engage 80 said stationary member, and pivoted means carried by said support and actuated by the weight of the well-tube for gripping the same.

8. In a well-sinking apparatus, the combination of a turntable comprising a lower stationary member and an upper rotary member, said stationary member having a central opening for the passage of the well-tube, a separable support adapted to non-rotatably engage 85 said stationary member, and devices pivotally carried by said support and extending upwardly and inwardly into engagement with the well-tube whereby the weight of the well-tube operates to force said 90 devices into engagement therewith.

9. In a well-sinking apparatus, the combination of a turntable comprising a lower stationary member and an upper rotary member, a plurality of sets of standards carried 100 by said turntable at opposite sides thereof, means for bracing the standards of each set, and pipe wrenches secured to one of the standards at each side of the turntable and engaging the well-tube.

10. In a well-sinking apparatus, the combination of a turntable comprising a lower stationary member and an upper rotary member, two sets of standards carried by 105 said turntable at opposite sides thereof, each of said sets comprising three standards, means for bracing the standards of each set together, and pipe wrenches connected respectively with the central standards of each 110 set and engaging the well-tube.

11. In a well-sinking apparatus, the combination of a turntable, gripping devices on opposite sides of the well-tube, and means for securing said gripping devices together for gripping the well-tube and rotating it with the turntable, one of said gripping devices comprising two cross-heads upon which said securing means bear, a gripping disk revolubly mounted between said cross-heads adapted to engage the well-tube, and another gripping disk revolubly mounted between said cross-heads in a different horizontal plane adapted to engage the well-tube, said cross-heads being adapted to rock on a horizontal axis relative to said securing means. 70
12. In a well-sinking apparatus, the combination of a turntable, gripping devices on opposite sides of the well-tube, and means for securing said gripping devices together for gripping the well-tube and rotating it with the turntable, each of said gripping devices comprising two cross-heads upon which said securing means bear, gripping disks revolubly mounted between said cross-heads in the same horizontal plane adapted to engage the well-tube, and other gripping disks revolubly mounted between said cross-heads in a different horizontal plane adapted to engage the well-tube, said cross-heads being adapted to rock on horizontal axes relative to said securing means. 80
13. In a well-sinking apparatus, the combination of a turntable, gripping devices on opposite sides of the well-tube, and means for securing said gripping devices together for gripping the well-tube and rotating it with the turntable, each of said gripping devices comprising two cross-heads upon which said securing means bear, gripping disks revolubly mounted between said cross-heads in the same horizontal plane adapted to engage the well-tube, and other gripping disks revolubly mounted between said cross-heads in a different horizontal plane adapted to engage the well-tube, said securing means comprising screws extending loosely through the oppositely-disposed cross-heads of said gripping devices, and means screwed on the outer ends of said screws for forcing said cross-heads together, said cross-heads being adapted to rock on horizontal axes relative to said securing means. 90
14. In a well-sinking apparatus, the combination of a turntable, gripping devices on opposite sides of the well-tube, and means for securing said gripping devices together for gripping the well-tube and rotating it with the turntable, each of said gripping devices comprising two cross-heads upon which said securing means bear, gripping disks revolubly mounted between said cross-heads in the same horizontal plane adapted to engage the well-tube, and other gripping disks revolubly mounted between said cross-heads in a different horizontal plane adapted to engage the well-tube, said securing means comprising screws extending loosely through the oppositely-disposed cross-heads of said gripping devices, and means screwed on the outer ends of said screws for forcing said cross-heads together, said cross-heads being adapted to rock on horizontal axes relative to said securing means. 100
15. In a well-sinking apparatus, the combination of a turntable, frames on opposite sides of the well-tube, gripping disks revolubly mounted on said frames and adapted to engage the well-tube, screws extending loosely through the oppositely-disposed ends of said frames, and means screwed on the outer ends of said screws for forcing said frames together, said frames being adapted to rock on horizontal axes relative to said screws. 105
16. In a well-sinking apparatus, the combination of a turntable, frames on opposite sides of the well-tube, gripping disks revolubly mounted on said frames, other gripping disks revolubly mounted on said frames in a different horizontal plane therefrom, screws extending loosely through the oppositely-disposed ends of said frames, and hand-wheels having globular heads screwed on the outer ends of said screws adapted to force said frames together but adapted to permit them to rock relative to the hubs. 95
17. In a well-sinking apparatus, the combination of a turntable having upright standards, transverse shafts mounted on said standards, rocking frames mounted upon the ends of said shafts and movable toward and from the well-tube, a pair of parallel shafts mounted in said frames at opposite sides of the well-tube, gripping devices carried by said parallel shafts, and means mounted on said transverse shafts and engaging said frames for forcing the gripping devices into engagement with the well-tube. 110
18. The combination of a base having a central opening and provided with an integral upright support surrounding said opening, with separable means adapted to be non-rotatably connected with said support for engaging the pipe and holding the same against rotation. 115
19. The combination of a base having a central opening and a stationary support surrounding said opening, with separable means adapted to be non-rotatably connected to said support and having gripping devices actuated by the weight of the pipe for gripping the pipe to hold it against rotation. 120
20. The combination of a base having a central opening and a stationary support surrounding said opening, with separable means adapted to be non-rotatably connected 125
- 15 disks revolubly mounted between said cross-heads in a different horizontal plane adapted to engage the well-tube, and other gripping disks revolubly mounted between said cross-heads adapted to permit them to rock relative to the hubs. 130

to said support and having pivotally-mounted gripping devices actuated by the weight of the pipe for gripping the pipe to hold it against rotation.

5 21. In a well-sinking apparatus, the combination with a turntable comprising a rotary member, of rocking frames mounted at opposite sides of the center of said turntable and connected with said rotary member and movable vertically independently thereof, and a plurality of gripping devices in different horizontal planes carried by each of said frames, said frames being movable independently of each other to carry 15 their gripping devices into and out of engagement with the pipe.

22. In a well-sinking apparatus, the combination of a turntable, means for rotating the same, a standard rising therefrom, and 20 a pipe wrench pivotally mounted on said standard and adapted to be carried around with the turntable for rotating a well-tube extending through the turntable.

23. In a well-sinking apparatus, the combination of a turntable, means for rotating the same, a standard rising therefrom, and a pipe wrench pivotally mounted on said standard and adapted to be carried around with the turntable for rotating a well-tube 30 extending through the turntable, and also adapted to be swung on said pivot out of engagement with the well tube.

24. In a well-sinking apparatus, the combination of a turntable, means for rotating

the same, a standard rising therefrom, a 35 clamp mounted on said standard having a horizontal opening therethrough, and a pipe wrench slidably mounted in said opening and adapted to be connected to a well-tube extending through the turntable. 40

25. In a well-sinking apparatus, the combination of a turntable, means for rotating the same, a standard rising therefrom, a sleeve adjustably mounted on said standard, a ring mounted on said sleeve, and a pipe 45 wrench slidably mounted in said ring and adapted to be connected to a well-tube extending through the turntable.

26. In a well-sinking apparatus, the combination of a base having an upright annular sleeve, a turntable fitted around said sleeve, anti-friction devices supporting said turntable, and a removable cover-plate fitted upon and non-rotatably engaging said sleeve. 50

27. In a well-sinking apparatus, the combination of a base having an upright annular sleeve, a turntable fitted around said sleeve, anti-friction devices supporting said turntable, a removable cover-plate fitted 60 upon and non-rotatably engaging said sleeve, and means carried by the turntable for gripping the well-tube. 65

MATTHEW T. CHAPMAN.
